UNITED STATES PATENT OFFICE.

GEORGE W. DONNING, OF EAST ORANGE, NEW JERSEY, ASSIGNOR OF ONE-HALF TO HARRY T. AMBROSE, OF ORANGE, NEW JERSEY.

SHIFTING DEVICE FOR PRINTING MECHANISMS.

SPECIFICATION forming part of Letters Patent No. 743,259, dated November 3, 1903.

Application filed February 10, 1903. Serial No. 142,789. (No model.)

To all whom it may concern:

Be it known that I, GEORGE W. DONNING, a citizen of the United States, residing at East Orange, in the county of Essex and State of New Jersey, have invented certain new and useful Improvements in Shifting Devices for Printing Mechanisms; and I do hereby declare the following to be a full, clear, and exact description of the invention, such as will enable others skilled in the art to which it app- pertains to make and use the same.

The object of this invention is to provide an improved form of shifting means in which a shiftable device may be set in a plurality of positions, and which when set in any one of a certain number of positions can be shifted to any of the other positions by certain actuating means, and which shifting means will automatically return to the said set position when the actuating means is released.

A further object of the invention is to provide in writing-machines, in connection with the type-carrying member thereof, (type-bar, type-wheel, or type-plate,) means by which such type-carrying member is rocked to position any of the plurality of characters carried by it.

A further object is to provide a yieldingly-adjustable member which in coöperation with shifting levers and mechanism constitutes an indicator or index of the adjusted position of said shifting mechanism by pointing to that particular shifting-lever whose operation would effect a similar positioning of the shifting mechanism.

A further object is to provide means for locking or retaining the adjustable member at any of the adjusted positions.

The invention is especially designed for a type-writing machine in which the type-carrying device carries a plurality of characters and where relative position of the type on each key to the printing-surface must be changed in order to print the different characters carried by the said device.

With these objects in view and other objects my invention consists of the constructions, combinations, and arrangements hereinafter described and claimed.

In the drawings forming a part of this application, and in which similar reference-sym-

bols indicate corresponding parts in the several views, Figure 1 is a side elevation of the type-writer. Fig. 2 is a detail view of parts shown in Fig. 1. Fig. 3 is a front elevation showing the type-bars with their shifting mechanism. Fig. 4 is a detail view of the semiring supporting means. Figs. 5, 6, and 7 show the shift-key levers. Fig. 8 shows a modified form of the parts shown in Fig. 1. Fig. 9 is a detail front elevation of the parts shown in Fig. 8. Fig. 10 shows part of the yieldable shifting means. Fig. 11 is a sectional view of the device of Fig. 10. Fig. 12 shows the rock-arms. Fig. 13 is an elevation of another form of yieldable shifting means. Fig. 14 is a view of the form shown in Fig. 13 from the opposite side. Figs. 15, 16, and 17 show the shift-key levers and connected parts in their several positions. Fig. 18 shows the lever carrying the notched link in two elevations. Fig. 19 shows the cam-link. Fig. 20 shows the link-carrying lever. Fig. 21 shows a detail of the slotted adjust-lever. Fig. 22 shows the latter lever from the opposite side. Figs. 23, 24, and 25 show the locking means for the adjust-lever; and Figs. 26 and 27 show the shift-levers and rock-arms in different positions.

Referring now to the drawings, and particularly to the parts shown in Figs. 1 to 11, A, B, and C represent three shift-key levers that may have a common pivotal axis A'. Retractile springs A² A³ A⁴ serve to return these levers when depressed. A rock-shaft D serves to operate any preferred form of shiftable device. I have shown it as operating a movable type-head carrying a plurality of characters, the type-bars E each carrying a pivoted head E², that is controlled by a lever E³, having an extension or tail piece E⁴. A semiring F is guided in slots F² in uprights F³. Rods or hangers F⁴ connect the semiring F with a semicircular supporting-strip F⁵, with which connects a bar F⁶. This bar is supported by one or more arms F⁶, pivoted on a transverse rod F⁷. The rock-shaft D has a crank D' connected to the arm F⁶. Consequently when the shaft D is rocked the semiring F will be raised and lowered. When the semiring is in the lowermost position, it does not engage the extension or tail piece E⁴;

but when it is raised in the slot F^2 it lies in the path of this extension and when the key-bar is operated will change the position of the type-head according to the distance it is 5 raised. I have in this instance provided three characters on the type-head. When the semiring is in the lower position, one of the characters will print. When the semiring is in the intermediate position, another character 10 will print, and when the semiring is in the upper position the other or third type will be brought into operating position when depressed. Preferably the lower position will be the normal position, causing the machine 15 to print the lower case. The intermediate position will cause capitals to be printed, and the upper position of the semiring will bring the numerals or punctuations into use.

One means of rocking the shaft D to bring 20 the semiring to these three positions is shown in Figs. 1 to 7. On the shaft D is secured a rock-lever having the two arms $D^3 D^4$. The arm D^3 carries a stud d , having a friction-roller thereon. The arm D^4 carries studs d^2 25 and d^3 , each having a friction-roller thereon. These latter studs are all arranged in alignment with the shift-levers A, B, and C. The lever A has a lug a arranged to strike the stud d when this lever is depressed. The lever 30 B has a lug b arranged to engage the stud d . This lever also has a lug b^2 arranged to engage the stud d^3 . The lever C has a lug c arranged to engage the lug d^2 . The levers A, B, and C have lugs a^3 , b^3 , and c^3 , respectively, each of which is arranged to strike the rock-shaft D, and thereby limit the downward movement of the levers.

The rock-lever is so secured to the rock-shaft D that when the semiring is in the lower 40 position its arms $D^3 D^4$ will be in the position shown in Fig. 1. When these arms are substantially horizontal, as shown in Fig. 26, the semiring will be in the intermediate position, and when the arms are in the position indicated in broken lines in Fig. 26 the semiring 45 is in the upper position.

The lugs a and a^3 are of such a length that if the rock-lever is in either of the positions shown in Fig. 26 or Fig. 27 upon depressing the 50 shift-lever A the lug a will engage the stud d and rock the shaft D to the position shown in dotted lines in Fig. 26, whereupon the lug a^3 will strike the shaft D and limit the movement of the shift-lever A. As before described, this will raise the semiring to its upper position, causing the machine to print numerals.

The lugs b and b^3 are so proportioned that if the rock-lever is in the position of Fig. 27 60 the lug b will engage the stud d and rock the shaft D until it is in the horizontal position, when the lug b^3 will impinge upon the shaft D, limiting its movement, thus raising the semiring to the intermediate position and 65 causing capitals to be printed; but should the rock-lever be in the position indicated in broken lines in Fig. 26 and the lever B be

depressed the lug b^2 will strike the stud d^3 and the shaft will be rocked to the position indicated in Fig. 27, when the lug b^3 , impinging upon the rock-shaft D, will limit the further movement of the lever. This will serve to bring the rock-lever to the horizontal position and cause the machine to print capitals. It will thus be noticed that this lever will 70 move the semiring from either of the extreme positions to the intermediate position, and the lugs c and c^3 are of such length that if the rock-lever is in either of the positions indicated in Fig. 26 on the lever C being depressed the lug c will strike the pin d^2 and move the arms until they are in the position indicated in Fig. 27, when the lug c^3 will impinge upon the rock-shaft. The lever C thus 75 serves to return the semiring to the lower position to print lower case when it has been moved to either of the other positions.

The lugs a , b and b^2 , and c constitute, respectively, independent shifting means, and the lugs a^3 , b^3 , and c^3 constitute stop devices 80 for limiting the depression of the shift-levers.

In order to adjust the rock-shaft in either of the three positions and at the same time yieldably retain it in each position, so that it may be moved from any of the adjusted positions to either of the other positions by the shift-keys just described, and yet will automatically return to the adjusted position upon the key being released, I have provided one form of means, as indicated in Fig. 1. An 90 adjusting-lever H is pivoted on a screw h and extends out so as to be moved in positions opposite the keys on the extremities of either of the levers A, B, or C. Stop-pins h^2 and h^3 limit the movement of the lever in either direction. A pin h^4 on the lever engages the side of the machine at holes h^5 , h^6 , and h^7 , at which positions the lever is temporarily locked 95 opposite one of the levers A, B, and C, respectively, whereby there is thus produced in connection and co-operating with the said shifting mechanism an indicator or index of the adjusted position of the shifting mechanism by pointing to the particular lever whose operation would effect such adjustment. For 100 instance, if the adjusting-lever points to the "Fig." shift-key it indicates that figures and punctuation-marks will be printed. When pointing to the "Cap." shift-key, it indicates operation in capitals, and when pointing to 105 the lower-case key it indicates normal position or for lower-case letters.

On the lever H are pivoted at h^8 bent levers or detents H^2 and H^3 , whose opposing extremities are connected by a spring H^4 , that tends to hold them against the screw h . A crank-arm H^5 is secured to the rock-shaft D and carries a pin H^6 , against which the opposing ends of the bent levers are yieldingly retained by the spring H^4 . When the lever H is moved in either direction, the crank H^5 110 will be rocked in the opposite direction, and it will be understood from the foregoing that 115 when the lever H is moved to a position op-

posite either of the shift-keys the shaft D will be rocked and the semiring shifted to a corresponding position. Upon depression of the key A when the lever H is in its lowest position the crank-arm H⁵ will be rocked downward and its pin H⁶ will force the bent lever H³ away from bearing on the screw h, as shown in Fig. 2. This will put the spring H⁴ under tension, as the lever H² is prevented from moving by the screw h, and when the key A is released the spring H⁴ will cause the lever H³ to move back against the screw h, which will rock the arm H⁵ upward, and thus through the rock-shaft move the semiring to its former position. If the shift-key B be depressed when the adjust-lever is in its lowest position, the arm H⁵ and lever H³ will be moved as just described, but not as far, since the shaft D is not rocked as much as when the key A was depressed, and key B will be returned when released. Again, if the adjust-lever be set in the intermediate position and the shift-key A be depressed the arm H⁵ and lever H³ will be moved as in the last instance and this key returned when released; but if the shift-key C is depressed while the adjust-lever is in this position the arm H⁵ will be moved upward, which will result in the pin H⁶ forcing the lever H² upward, while the arm H³ will remain in contact with the pin h, putting the spring H⁴ again under tension, that will return the key C and semiring to the adjusted intermediate position when the key is released. Finally, if the adjust-lever is moved to its upper position and the shift-key B is depressed the arm H⁵ and lever H² will be given the same movement as just described, putting the spring again under tension, which will return this key and semiring to the adjusted position, and if the shift-key C is depressed while the adjust-lever is in this position then the arm H⁵ and lever H² will be moved as just described, but to a greater distance, and upon this key being released it and the semiring will be returned to the said adjusted position by the spring.

A modification of the yieldable adjusting means just described is shown in Figs. 8 to 12. Here an adjust-lever K is pivoted onto the rock-shaft D. Two bent levers K² K³ are pivoted on the lever K similar to the levers H² H³. Their opposite ends are held by a spring K⁶ against a pin K⁵ on an arm K⁴, secured to the shaft D. It will be observed that the arm K⁴ does not extend toward the adjust-lever, but in the opposite direction. Hence when the lever K is in the lower position, as shown in Fig. 8, the semiring will be set in the upper position and the machine will print figures, and when the adjust-lever is in the upper position the machine will print lower case; otherwise the operation of the arms K² K³ and spring K⁶ is the same as the parts shown in Fig. 1. Indicating-lugs k, k², and k³ are disposed in alinement with

the lever K when in its respective positions of adjustment.

Another form of yieldable adjusting means is shown in Fig. 13 and following. On the shaft D is secured an arm L, that carries a stud L², having a friction-roller l thereon. Three shift-levers M, N, and P are used instead of the levers A, B, and C and are shown in Figs. 15, 16, and 17, respectively. The lever M has a cam-surface M², limited by a stop M³ and arranged to engage the stud L² when the arm L is in position to cause the semiring to be in either its upper position, as shown in Fig. 17, or in its intermediary position, as shown in Fig. 15, and swing the arm L into the position shown in Fig. 16, thereby rocking the shaft D to lower the semiring in its lower position for printing lower-case characters. The lever N is provided with two cam-faces N² N³, so arranged that when the arm is either in the position of Fig. 16 or that of Fig. 17, with the semiring set to print either lower case or numerals, the cam will strike the stud L² and force the arm to the position indicated in Fig. 15, and the semiring will be moved to the intermediate position. The third lever, P, has a cam-surface P², limited by a stop P³, and so arranged that when the arm L is in either the position of Fig. 15 or Fig. 16 the cam will engage the stud L² and move the arm to the position indicated in Fig. 17, thus shifting the semiring from either its intermediate or lower position to the upper position, in which numerals will be printed.

For the purpose of adjusting the arm L in either of the three positions and yieldingly retaining it in this position I have provided a link R, pivoted by screw r to a lever S, that is pivoted on a pin S². The link R has two cam-surfaces R² R³, in the angle of which the stud L² is yieldingly retained by a retractile spring T, connecting said link R with the lever S near its axis. A lever V is pivoted at V² and has a cam-slot V³, which engages the screw r. When the lever V is in alinement with the key end of lever N, the arm L will be in the middle position, as shown in Figs. 13 and 14. When the lever V is moved up in alinement with the end of lever M, the lever S will be moved forward and also the link R, which will rock the arm L to the position indicated in Fig. 16, and if the lever V is moved to its upper position the lever S and link R will move rearward and the arm L will be moved to the position in which it is shown in Fig. 17. Now if the arm L is in the position shown in Fig. 13 and the shift-lever M is depressed the cam-surface M² will engage the stud L² and rock the arm L forward. This movement of the arm L will cause the stud L² to engage the cam-surface R² and rock the link R upward on the screw r and will extend the spring T, putting it under still greater tension. Upon the key-lever being released the spring will cause the cam R² to force the stud to its nor-

mal position in the angle of the cams R^2 R^3 , while if the lever P is depressed and the arm L moved to the position shown in Fig. 17 the stud L^2 will engage the cam R^3 , which will also 5 rock the link R and extend the spring T , and upon this key being released the cam R^3 will return the arm L to its set position, as before. When the lever V is set in the upper position, the link will be set to normally retain the arm 10 L in the position shown in Fig. 17. Upon depressing either the lever M or N the cam M^2 or cam N^2 will engage the stud L^2 and raise the link R , and upon the release of these 15 keys the spring will cause the cam R^2 to return the arm L to the adjusted position. Should the lever V be set in the lower position, the link will be moved normally to retain the arm L in the position shown in Fig. 16, and upon either the lever P or the lever 20 N being depressed the cam P^2 or cam N^2 will engage the stud L^2 and raise the link R , and upon the release of the levers the spring T will cause the cam R^3 to return the arm L to its adjusted position. To lock the lever in 25 its three positions of adjustment, the lever V is notched or countersunk at V^3 , V^4 , and V^5 . The screw r has a conical portion r^2 , that is forced into the notches V^3 V^4 V^5 by a plate-spring r^3 , secured to the screw r by a screw r^4 . 30 In the modified form it is obvious that the selecting lugs or projections on the lower edges of the shifting-levers of the principal construction (illustrated in Figs. 1 to 12, inclusive) find counterpart in the cam-lugs in 35 the construction of Figs. 13 to 27, wherein the lugs are simply brought nearer together and turned to present their working face to operate on opposite sides of a single arm, which takes the place of the two opposingly-extending arms in the first form. 40

It is to be understood that the improved shifting mechanism herein shown and described has application in all situations where it is necessary to shift and lock a movable 45 part and then temporarily return it to its normal position or shift to a third position, so that when operation is completed there it will automatically return, say, to the second position, to which it has been shifted and 50 locked. Therefore it may be employed in round-platen type-writers wherein the type-bar remains at a fixed fulcrum-point and a shiftable platen-carrier is operated by a transverse vibratory rod connecting therewith, in 55 which form it may be desirable to shift the platen-carrier for printing a capital letter or figure or other character; furthermore, in writing-machines wherein a type-wheel is employed and which is to be shifted for different kinds of printing; furthermore, in machines wherein the type-bars are housed 60 within a shiftable basket and the platen is stationary. It is also to be understood that I may utilize other means than those 65 scribed and shown and yet be within the spirit of my invention, which is to provide a device for shifting a shiftable or vibratory

part and while shifted to lock it there temporarily and yet in such manner that should it be desired, the shiftable part may be moved to a first or third position temporarily and normally held there until released, when the shiftable part will return to its locked position, wherever that might be. 70

Having thus fully described my invention, 75 what I claim as new, and desire to secure by Letters Patent, is—

1. The combination with a printing mechanism, of a device arranged to be shifted to a plurality of positions, a plurality of shifting means, each constructed to shift said device into one of its positions, and adjusting means 80 constructed and arranged to adjust and yieldingly retain said device in any of its several positions, substantially as described. 85

2. The combination with a printing mechanism, of a device arranged to be shifted to a plurality of positions, a plurality of shifting means, each constructed to shift said device into one of its positions, and adjusting means 90 constructed and arranged to adjust and yieldingly retain said device in any of its several positions and to return said device to its adjusted position from any of the other several positions into which said device may be shifted, substantially as described. 95

3. The combination with a printing mechanism, of a device arranged to be shifted to a plurality of positions, a plurality of shifting means, each constructed to shift said device 100 into one of its positions, and adjusting means constructed and arranged to adjust and yieldingly retain said device in any of its several positions and to automatically return said device to its adjusted position from any of the 105 other several positions into which said device may be shifted, substantially as described. 110

4. The combination with a printing mechanism, of a device arranged to be shifted to a plurality of positions, an independent shifting means controlling each of such plurality of positions, each shifting means constructed to shift said device from the positions controlled by any other of said shifting means, and adjusting means constructed and arranged to adjust and yieldingly retain said device in any of its several positions, substantially as described. 115

5. The combination with a printing mechanism, of a device arranged to be shifted to a plurality of positions, an independent shifting means controlling each of such plurality of positions, each shifting means constructed to shift said device from the positions controlled by any other of said shifting means, 120 and adjusting means constructed and arranged to adjust and yieldingly retain said device in any of its several positions and to return said device to its adjusted position from any of the other several positions into which 125 said device may be shifted, substantially as described. 130

6. The combination with a printing mechanism, of a device arranged to be shifted to a

plurality of positions, an independent shifting means controlling each of such plurality of positions, each shifting means constructed to shift said device from the positions controlled by any other of said shifting means, and adjusting means constructed and arranged to adjust and yieldingly retain said device in any of its several positions and to automatically return said device to its adjusted position from any of the other several positions into which said device may be shifted, substantially as described.

7. The combination with a printing mechanism, of a shiftable device arranged to be shifted to a plurality of positions, a plurality of shifting means therefor, and an adjusting means constructed to adjust said device in any of its several positions and to coöperate with said shifting means to indicate the position of said shiftable device, substantially as described.

8. The combination with a printing mechanism, of a rock-shaft, a lever operating through intermediary connections to rock said rock-shaft and arranged to adjust it in a plurality of positions, engaging means carried by said rock-shaft, an independent shifting means controlling each of such plurality of positions, each shifting means constructed to actuate said engaging means from the positions controlled by the other several shifting means, a plurality of shift-levers constructed each to actuate one of said shifting means, substantially as described.

35 9. The combination with a printing mechanism, of a rock-shaft, a lever operating through intermediary connections to rock said rock-shaft into a plurality of positions, engaging means carried by said rock-shaft, an independent shifting means controlling each of such plurality of positions, each shifting means constructed to actuate said engaging means from the positions controlled by the other several shifting means, a plurality of shift-levers constructed each to actuate one of said shifting means, and means carried by said shift-levers to limit their movement, substantially as described.

10. The combination with a printing mechanism, of a rock-shaft, means constructed to rock said rock-shaft to a plurality of positions, engaging means carried by said rock-shaft, an independent shifting means controlling each of such plurality of positions, each shifting means constructed to actuate said engaging means from the positions controlled by the other several shifting means, and a plurality of shift-levers constructed each to actuate one of said shifting means, substantially as described.

11. The combination with a printing mechanism, of a rock-shaft, a lever arranged to adjust said rock-shaft in a plurality of positions, a resilient connection between said lever and rock-shaft and constructed to permit swing of the rock-shaft in either direction and

to return it therefrom, substantially as described.

12. The combination with a printing mechanism, of a rock-shaft, an adjust-lever arranged to rock the shaft and set it in a series of positions, a number of shift-levers each arranged to rock the shaft and move it to one of said positions when the shaft has been set in any of the other said positions by the adjust-lever, the adjusting member and the shifting members coöperating to indicate the position of the rock-shaft, substantially as described.

13. The combination with a printing mechanism, of a rock-shaft, an arm secured to the shaft, an adjust-lever, a resilient connection between the arm and lever arranged to cause the lever to set the shaft in a series of positions, a number of shift-levers, lugs on the shift-levers, a rock-lever on the rock-shaft, studs on said rock-lever and arranged to be engaged by the lugs of the shift-levers, said lugs and studs being arranged to cause each of said levers, when depressed, to rock the shaft and move it to one of said positions when set in any of the other positions by said adjust-lever, substantially as described.

14. The combination with a printing mechanism, of a rock-shaft, an arm secured to the shaft, an adjust-lever, a resilient connection between the arm and lever arranged to cause the lever to set the shaft in a series of positions, a number of shift-levers, lugs on the shift-levers, a rock-lever on the rock-shaft, studs on said rock-lever and arranged to be engaged by the lugs on the shift-levers, said lugs and studs being arranged to cause each of these shift-levers, when depressed, to rock the shaft and move it to one of said positions when set in any of the other positions by said adjust-lever, and a lug on each shift-lever arranged to strike the rock-shaft and limit the depression of the lever, substantially as described.

15. The combination with a printing mechanism, of a rock-shaft, an adjust-lever, an arm secured to the shaft, a resilient connection between the arm and lever arranged to cause the lever to move the shaft to each of three positions, a rock-lever on the rock-shaft, studs on said rock-lever, a shifting-lever having a lug arranged to engage one of said studs and rock the shaft to one of said positions when the shaft has been set in either of the other positions, a second shift-lever having a lug arranged to engage one of said studs and rock the shaft to another of said positions when set in either of the other positions, and a third shift-lever having a lug arranged to engage one of said studs when the shaft has been set by the said first-mentioned shift-lever and rock it to a position intermediate of the position set by the said levers, the said third shift-lever having another lug arranged to engage one of said studs when the shaft has been set by the said second lever and

rock the shaft to said intermediate position, substantially as described.

16. The combination with a printing mechanism, of a rock-shaft, a pin, an adjust-lever pivoted on the pin, a pair of levers pivoted on the adjust-lever and extending on opposite sides of said pin, a spring connecting said latter levers and arranged to normally retain them in contact with the pin, an arm on the rock-shaft, a pin on said arm arranged to lie between adjacent ends of said pair of levers and in engagement therewith, substantially as described.

17. The combination with a printing mechanism, of a rock-shaft, a pin, an adjust-lever pivoted on the pin, means for locking the lever in a series of positions, a pair of levers pivoted on the adjust-lever and extending on opposite sides of the pin, a spring connecting said latter levers and arranged to normally retain them in engagement with said pin, an arm on the rock-shaft, a pin on said arm arranged to lie between the adjacent ends of said pair of levers and in engagement therewith, a series of levers constructed to rock the shaft and move it to a series of positions, substantially as described.

18. The combination with a printing mechanism, of a rock-shaft, a pin, an adjust-lever pivoted on the pin and arranged to be locked in a series of positions, a pair of levers piv-

oted on the adjust-lever and extending on opposite sides of the pin, a spring connecting said latter levers and arranged normally to retain them in engagement with the pin, an arm on the rock-shaft, a pin on said arm arranged to lie between the adjacent parts of the said pair of levers and in engagement therewith, a series of levers constructed respectively to rock the shaft and move it to the same positions to which moved by said adjust-lever, substantially as described.

19. The combination with a printing mechanism, of a rock-shaft, an adjust-lever arranged to rock the shaft and set it in a series of positions, a number of shift-levers each arranged to rock the shaft and move it to one of said positions when the shaft has been set in the other positions by the adjust-lever, the adjust-lever being arranged to coöperate with said shift-levers to indicate the position of the rock-shaft, and means for automatically returning the shaft to any of its adjusted positions when moved therefrom by any of the said shift-levers, substantially as described.

In testimony whereof I affix my signature in the presence of two subscribing witnesses.

GEORGE W. DONNING.
